(57) **CLAIM**

The ornamental design for a billiards stroke practice cube substantially as shown and described.

DESCRIPTION

FIG. 1 is a top-right-front isometric view of a billiards stroke practice cube;

FIG. 2 is a bottom-left-back isometric view thereof;

FIG. 3 is a top-right-front view of the billiards stroke practice cube of FIG. 1 held on a hand; and,

FIG. 4 is a front view of the billiards stroke practice cube of FIG. 1.

The broken line showing small circles and rectangles on circular pads is for the purpose of illustrating portions of the billiards stroke practice cube and forms no part of the claimed design, and the broken line showing a hand in FIG. 3 is for the purpose of illustrating environmental structure and forms no part of the claimed design.

1 Claim, 4 Drawing Sheets
